FREDERICK C. DOLCATER, OF WASHINGTON, DISTRICT OF COLUMBIA, ASSIGNOR, BY
MESNE ASSIGNMENTS, TO ADDRESSOGRAPH COMPANY, OF CHICAGO, ILLINOIS, A
CORPORATION OF ILLINOIS.

PRINTING APPARATUS WITH ADDING MECHANISM.

1,301,235.

Specification of Letters Patent.

Patented Apr. 22, 1919.

Application filed March 15, 1915, Serial No. 14,539. Renewed March 6, 1919. Serial No. 281,071.

To all whom it may concern:

Be it known that I, FREDERICK C. DOLCATER, a citizen of the United States, residing at Washington, District of Columbia, have invented certain new and useful Improvements in Printing Apparatus with Adding Mechanism, of which the following is a specification.

My present invention relates to means for selecting and transferring number items from record plates onto item wheels as said plates are passed *seriatim* through the addressing or printing apparatus of which they form a part, and in this respect my present invention is similar in its broad features to that disclosed in application for Letters Patent of the United States filed by me August 5, 1914, #855,238.

In the accompanying drawings;

20 Fig. 1 is a plan view of so much of a printing machine as is necessary to an understanding of my invention.

Fig. 2 is a detail sectional view of certain of the parts enlarged.

25 Fig. 2^a is a plan view of part of a printing record or address plate with selective means to determine the value represented by the plate and which is to be transferred to the accumulator mechanism.

30 Fig. 3 is a cross sectional view of the machine with parts in elevation.

Fig. 4 is a plan view of a simpler form of machine in which the plates are fed and moved by hand.

35 Fig. 5 is a sectional view of such machine.

Fig. 6 is a bottom plan view showing the mechanism for operating the chain feed of the printing plates.

40 While I have shown the invention in connection with a hand operated printing or addressing machine, it will be understood that I do not restrict myself to the use of the invention with such form of machine, as it may be used in connection with a power operated machine.

The record or address plates which I show are of the well known Montague type though other forms of plates or printing members may be used.

45 In carrying out my present invention, I utilize the plates as the means for controlling the item transferring or setting members and while this may be done in various ways, in the particular form illustrated

in Figs. 1, 2 and 3 as an exemplification of my invention the movement of the printing plates themselves imparts to the item members their setting-up action.

In the drawings, 1 indicates the printing plate and 2 the guide-way along which the plates are moved. This guide-way is adapted to receive the depressed margins 3 of the plate as in ordinary practice and the plates may be fed along this way by any suitable means as by a reciprocating shuttle bar or an endless chain. For convenience I show a chain feed 4, this being provided with dogs as in ordinary practice which singly take hold of the bottom plate of the pile *a* in the hopper 5 and move the plates step by step to the impression point under the impression head 6 carried by an impression arm 7. As I have chosen for convenience to show the invention in connection with a hand operated machine this impression arm is pivotally mounted at 8 and is operated by a handle 9 at or near the impression head. An inking ribbon is shown at 10, this extending over the impression point and then rearwardly at its ends to ribbon spools 11 which are operated in any suitable manner from the pivoted end of the impression arm but as this forms no part of the present invention, it is unnecessary to describe these features in detail.

45 The record plates have selecting means indicating their values and adapted to control the item setting mechanism.

This item mechanism may be of various forms and as the details of the item wheels, accumulator mechanism and carrying mechanism may be of any suitable kind well-known in the art of calculating or adding machines, I deem it unnecessary to describe these features herein.

50 The item wheels, representative of any suitable organization for the purpose, are indicated at 12, there being five denominations of these and the printing plates are each provided with a space at the right, in which space the selecting openings 13 are punched according to the value the plate represents. The plate on one side may be marked off in blocks indicated by the dotted lines in Fig. 2^a, there being five rows, as an example, one way and nine rows the other way, each latter row representing the digits 1 to 9 inclusive. The item wheels are those ordinarily em-

ployed, each having digits running from 0 to 9 inclusive. The order of digits in each column on the plate run from right to left and longitudinally of the plate in indicating 5 the digits 1 to 9.

Suppose the value of the plate in Fig. 2^a to be \$2.59, the said plate would have its selecting means or openings disposed as those represented and these would be set up on the 10 item wheels 12. The item mechanism besides the item wheels 12 includes a gear wheel 14, one for each item wheel, and those gear wheels are engaged by racks 15, one for each item wheel. These racks are formed on bars 15 16 jointed at 17 and each bar has its end 18 upturned and adapted to enter the selecting openings in the printing plate whenever an opening is presented above the end of a bar and said bar is moved upwardly. 20 The bars are arranged side by side, and there is a spring 19 for each bar tending to pull the slide to the right in Fig. 2. Springs 19^x tend to lift the arms 18 of the slides. Three of the slides are represented in Fig. 25 2 as having been pulled to the left and as having respectively operated the item wheels to indicate the digits 259.

Normally all the slides are in the position indicated at *b* in Fig. 2, that is, they are 30 at the right hand limit of their stroke, when normal. They are all raised, however, to the height indicated by the slide *c*. In feeding the plates leftward from the hopper 5, it is necessary that the plates be moved over 35 the slides without causing the front edge of the plates to contact with and draw the slides forward or to the left and thereafter, the front ends of the slides must rise through the openings in the plate and be moved by 40 the plate in the final part of the plate's step movement. When the plate, therefore, performs its movement, all of the slides must first be depressed from their high position to allow the front edge of the printing plate 45 to pass it. This is done by an arm 20 on a rock shaft 21 which extends transversely over all the slides, said rock shaft being operated by an arm 22 controlled by a spring 23 and by an arm 24, the latter being connected with the pivoted end of the impression arm. The arm 24 underlies and the spring overlies the arm 22. As in previous 50 forms of addressing machines, the feed of the record plates takes place when the impression head rises, and in the present instance, the printing plate would begin to move to the left from the hopper during the first part of the upward movement of the impression arm and would continue so to move during the last half upward stroke 55 of the said impression arm.

As the first part of the movement of the plates must be ineffective and only the subsequent or last portion of the plate's movement is utilized to operate the item trans-

ferring slides, I depress all of the slides during the last half of the downward movement of the impression arm, and hold them down until the impression arm has reached the middle of its upstroke and because the printing plate begins its movement to the left with the beginning or substantially the beginning of the upward movement of the impression arm, the forward edge and forward portion of the record plate will have passed 70 over the depressed slides without effect by the time the impression arm reaches the middle of its upstroke and as the arm 24 now comes in contact with the arm 22 the controlling bar 20 will be raised and all the slide 75 bars at their ends 18 will have an upward tendency owing to the pressure from the springs 19^x and the pivot connection of the slides and if an opening occurs in the plate above any bar the upturned end of this bar 80 will enter the opening and will thus be selected for operation by the continued movement of the plate to the left and this movement will be imparted to the item counting wheels and the values will be indicated 85 90 thereon.

It will be clear that the bars will be moved distances corresponding to the location of the selecting openings in the plate with which the bars contact.

Fig. 2 represents the record plate at the end of its one step movement to the left.

Now in order to restore the item bars to their normal positions, they are depressed from engagement with the printing plate by the rod 20 and arm 22 and spring 23 when the impression arm reaches about the middle of its downward stroke the arm 24 then having lowered far enough to allow the arm 20 to contact with and depress the item slides 105 at their left hand end.

When free from the printing plate, the slides which have been operated will move to the right back to normal position under the tension of their springs and as these 110 slides in this action will turn the item wheels back to normal position it will be necessary at this time to transfer the values from the item wheels which have been operated onto accumulator mechanism and this accumulator mechanism may be of any suitable kind. I indicate diagrammatically in Fig. 2 accumulator wheels at *c'*. These may have gears or teeth which are thrown into gears or teeth on the item wheels before these are 115 returned to normal position so that in this returning action the values on the item wheels will be transferred to the accumulator mechanism and when the item wheels have reached normal position and the values 120 have been transferred, the accumulator mechanism will be thrown out of connection with the item wheels, and these will be left 125 in position to be set up by the next plate. Any suitable form of carrying mechanism 130

may be used for the accumulator mechanism for carrying from order to order. This accumulator and carrying mechanism may be like that shown in Letters Patent of the 5 United States granted to George W. and A. L. Dudley November 4, 1902, #712,777 or S. B. Austin, an example of the latter's invention along this line being shown in Patent #1,071,382, August 26, 1913, it being understood 10 that slight modification of said mechanism will be made to throw the accumulator wheels into and out of connection with the item wheels but as my invention does not relate to such adding mechanism *per se* but 15 to a selective address or record plate and item connections controlled thereby I do not disclose herein such adding mechanism in detail. It is sufficient for the purpose of my invention to show how the record plates will 20 transfer their values onto item wheels, the further transfer of these items onto accumulator wheels from the item wheels relating to the adding mechanism itself, which as above stated, does not form a part of my 25 present invention.

In Figs. 4 and 5 I show a form of machine in which the plates are placed one by one by hand and likewise removed.

A carrier 26 is movably mounted to receive 30 the plates and after a plate is placed in position thereon, by pressure of the hand, the carrier together with the plate is moved rearwardly under the inking ribbon and to the impression point and a hand operated lever 35 is then brought down to make the impression. I utilize the movement of the plate as just described to transfer its values onto item wheels and for this purpose, I use a series of item slides 26' having upturned 40 ends to engage openings in the plates when the plates come into position over these slides. The slides are spring mounted so that their forward ends may be depressed to allow the depressed margin of the plate 45 in the rear movement thereof to pass over the depressed upturned ends of the item slides.

For depressing the slides I employ a lever 27 pivoted at 28 to the frame and having 50 an arm 29 reaching over the item slides, the said lever being operated by a pin *d* on the plate carrier engaging a suitable cam or incline on the lever, said plate carrier being marked 26 and the cam 31. The arrangement 55 is such that after the plate has moved far enough rearward so that its depressed margin has passed over the depressed item slides, these slides can then rise and bear against the underside of the plate and then 60 in the continued movement of the plate, any slide which has found an opening will engage the same by its upturned end under the pressure of the spring 32 and during the balance of the rearward movement of the 65 plate, the item will be transferred to the

item wheel. After the printing operation has been performed on the plate and this is drawn forwardly, the item wheels which have been advanced will be returned to normal position and having thrown into connection with these item wheels accumulator wheels, the values will be transferred from the item wheels onto the accumulator mechanism in a manner similar to that described above in connection with the other form of 70 the machine. As the printing plate with its carriage is drawn forward, the item slides will be depressed by the cam 31 and lever 27, 29 to allow the depressed margin of the printing plates to pass over the upturned 80 ends of the item slides without having any effect thereon.

It will be observed that in both forms of the machine, the movement of the printing plate is utilized to transfer its value onto 85 item wheels and adding mechanism.

The step by step movement of the plates is effected by moving the feed chain step by step through mechanism operated from the arm 24. This mechanism is fully shown in 90 Letters Patent of the United States granted to the assignee of the present applicant, No. 1,215,040, dated February 6, 1917, the arm in said patent corresponding to the arm 24 herein being there indicated at 15. 95

As shown in Fig. 6 the plate feed chain passes around wheels, one of which is shown at 36, on a shaft 37, which is operated step by step in one direction by pawl and ratchet mechanism, indicated generally at 38, this mechanism being driven through gearing 39 from a rock shaft 40, which has an arm 41 engaged by the arm 24 connected with the impression arm 7. Oscillating movement of the impression arm will be imparted to the 100 pawl and ratchet mechanism, so that the shaft 37 will be turned step by step, but always in one direction to give the feed chain its step by step feeding action, this mechanism being old, as in the patent of 105 Lee, mentioned herein, No. 1,215,040. 110

I claim as my invention:

1. In combination in a printing machine, impression means, a series of printing plates, a hopper for the plates, a plate feeder for 115 moving the plates step by step from the hopper to and past the impression means, said printing plates having value selecting means thereon, and item mechanism engaged by the selecting means and operated 120 by one of the step by step movements of the printing plate, substantially as described.

2. In combination in a machine of the class described, impression means, a series of printing plates, a hopper therefor, a 125 feeder for the printing plates to move them step by step to and past the impression means, said plates having value selecting means, item mechanism including item wheels and item slides, said item slides be- 130

ing adapted to engage the selecting means on the plates and be moved by one of the step by step movements thereof, said item slides being connected with and operating 5 the item wheels, substantially as described.

3. In combination, impression means, printing plates having value selecting means, feed means for the plates moving them step by step past the impression means, item 10 mechanism to be engaged by said selecting means and to be operated by the plate in the movement of said plate and controlling means for the item mechanism to prevent engagement with the edge or other portion 15 of the plate, said controlling means allowing the item mechanism to engage the plate after the plate has moved into position thereover, substantially as described.

4. In combination, impression means, 20 printing plates having openings serving as value selecting means, item mechanism to engage the said openings, means for moving the plates step by step, controlling means for the item mechanism to prevent engagement 25 with the plate at predetermined times, and to allow engagement at predetermined times, the operation of said item mechanism being initiated by the movement of the plate, and in accordance with the disposition 30 of the selecting openings on said plate, substantially as described.

5. In combination, a table having a straight run-way for printing plates, a hopper at one end of said run-way, an impression member operating to and from the run-way, means for feeding the printing plates step by step from the hopper along the run-way to and past the impression means, said printing plates having value selecting means, item mechanism arranged adjacent the said run-way to be set by and during the movement of the printing plates along the runway from one position to another, said item mechanism in this setting 45 action being engaged with the value selecting means of the printing plates, and means for releasing the item mechanism from the printing plates and restoring the item mechanism to normal position, said means operating in a prescribed relation to the impression member, substantially as described.

6. In combination, a table having a run-way for printing plates, a hopper for said plates, an impression member movable toward and from the run-way, a feeder for the printing plates for moving them step by step along the run-way, said printing plates having value selecting means, a series of item members to engage the said value selecting means, means for initially depressing the said item members to allow the printing plates to pass into position above them and for again depressing the item members for releasing the item members from the plates, 60 said means being controlled by the move-

ment of the impression arm, and restoring means for the item members, substantially as described.

7. In combination, a table having a run-way for printing plates, a hopper for said plates, an impression member movable toward and from the run-way, means for feeding the plates step by step along the run-way to and past the impression member, said printing plates having value selecting 75 means, a series of item members to engage the value selecting means, means for depressing the said item members and a connection between the said depressing means and the impression member, substantially as de- 80 scribed.

8. In combination in a printing machine, printing plates, means for carrying them to the impression point, said printing plates having value selecting means thereon, item 85 mechanism arranged below the path of the plate but having portions projecting up into said path to engage the value selecting means, depressing means for the item mechanism to allow the printing plate to pass 90 above the same, said means being automatically operated in a prescribed relation to the movement of the printing plate, said plate in its further movement operating said item mechanism, substantially as described. 95

9. In combination in a printing apparatus, printing plates having depressed margins and value selecting means, a table having a run-way, the said depressed margins engaging under a portion of said run-way and 100 holding the plates against upward displacement, item mechanism arranged below the run-way and to engage the plates from beneath the same, means for feeding the plates along the run-way to and past the impression point and impression means, the said plates controlling the item mechanism, sub- 105 stantially as described.

10. In combination impression means, printing plates having value selecting means, 110 feed means for the plates moving them step by step past the impression means, item mechanism to be engaged by said selecting means and to be operated by the plate in the movement of said plate and controlling 115 means for the item mechanism to prevent engagement with the edge or other portion of the plate, said controlling means allowing the item mechanism to engage the plate after the plate has moved into position thereover, 120 said controlling means being operated from the impression means during certain periods only of the movement of said impression means, substantially as described.

11. In combination in a printing ma- 125 chine, means for moving printing plates to an impression point and value selecting means on the printing plates arranged at different points longitudinally and laterally thereof, item mechanism comprising a series 130

- of members to engage said value selecting means as the plate moves, said item members having their plate engaging ends arranged normally in the same plane transverse to the line of movement of the plates, said item members moving individually and to different degrees by their engagement with and by and during the further movement of the plate, substantially as described.
12. In combination in a printing machine, means for moving printing plates to an impression point and value selecting means on the printing plates, item mechanism comprising a series of members to engage said value selecting means as the plate moves, said item members moving individually and to different degrees by their engagement with and by and during the further movement of the plate, and controlling means for depressing the item members from engagement with the plate to allow them to return to normal position and to permit the plate to have further movement, substantially as described.
13. In combination in a printing machine, impression means, means for moving printing plates to the impression point and value selecting means on the printing plates, item mechanism comprising a series of members to engage said value selecting means as the plate moves, said item members moving individually and to different degrees by their engagement with and by and during the further movement of the plate, and controlling means operated from the impression means for depressing the item members from engagement with the plate to allow them to return to normal position and to permit the plate to have further movement, said controlling means operating to depress the item members to release them from the printing plates while the said printing plate is at rest and during the stroke of the impression means.
